Primary Examiner — Robin V Webster(74) *Attorney, Agent, or Firm* — Woodard, Emhardt, Moriarty, McNett & Henry LLP; William McKenna; Kenneth Gandy(57) **CLAIM**

The ornamental design for a fire sprinkler head guard, as shown and described.

DESCRIPTION

FIG. 1 is a front perspective view of the fire sprinkler head guard showing the new design, the rear perspective view is a mirror image of the illustrated front perspective view; FIG. 2 is a rear plan view of the fire sprinkler head guard showing the new design, the front plan view is a mirror image of the illustrated rear plan view; and, FIG. 3 is a left side view of the fire sprinkler head guard showing the new design, the right side view is a mirror image of the illustrated left side view. The broken line showing of environmental structure is included for the purpose of illustrating and forms no part of the claimed design.
